UNITED STATES PATENT OFFICE.

HENRY C. EGERTON, OF PASSAIC, NEW JERSEY, ASSIGNOR TO WESTERN ELECTRIC COMPANY, INCORPORATED, OF NEW YORK, N. Y., A CORPORATION OF NEW YORK.

PHONOGRAPH-TRANSMITTER.

1,303,183.

Specification of Letters Patent.

Patented May 6, 1919.

Application filed March 13, 1916. Serial No. 83,869.

To all whom it may concern:

Be it known that I, HENRY C. EGERTON, a citizen of the United States, residing at Passaic, in the county of Passaic and State of New Jersey, have invented certain new and useful Improvements in Phonograph-Transmitters, of which the following is a full, clear, concise, and exact description.

This invention relates to phonograph transmitters, and more particularly to transmitters wherein currents generated in an electromagnetic system by the vibrations of a tracing stylus act in a telephone receiver to produce speech or other sounds present, as recorded on a phonograph record.

One object of this invention is to provide a highly efficient magneto-inductive current generating system of this character, in which the effective movements of the tracing stylus are of greater amplitude than the resulting movements of the armature in the magneto-inductive system.

Another object of this invention is to provide an improved phonograph transmitter adapted to be assembled in a small symmetrically formed inclosing case of such convenient shape and size as best adapted to withstand the handling to which phonograph transmitters are necessarily subjected, and to better meet and perform the service operations for which they are intended.

A further object of this invention is to provide an improved phonograph transmitter which may be interchangeably positioned to reproduce sound vibrations from either a so-called vertically grooved record or a transversely grooved record.

In accordance with this invention a magneto-inductive system, comprising a plurality of pole members, magnetizing coils, and current reproducing coils, is provided with an armature of a relatively considerable mass. The armature rests centrally on one of the pole members, and is adapted to execute a rocking motion of limited amplitude in the magnetic circuit zone of the several pole members, in response to vibrations transmitted thereto by means of a motion reducing leverage system interposed between the tracing stylus and the armature. Currents correspondingly varying in strength and direction are thereby induced in the current reproducing coils. Therefore a telephone receiver included in a circuit with these coils will be operated to repeat the tones

represented by the groove on the phonograph record.

In the accompanying drawing, Figure 1 represents, partially in perspective, a side sectional view of a completely assembled transmitter. Fig. 2 is a similar view showing the transmitter turned one-quarter or ninety degrees to the left of the position shown in Fig. 1. Fig. 3 is a diagram of the circuit and connections of the magneto-inductive system of this transmitter. Fig. 4 shows, on an enlarged scale, a transversely cut groove of a phonograph record, which is the style of record adapted to be traced when the transmitter stylus is in the position shown in Fig. 70 1, and Fig. 5 shows a vertically cut groove of a phonograph record, which is the style of record adapted to be traced when the transmitter stylus is in a position corresponding with that shown in Fig. 2.

Referring to the drawing, the reference numeral 1 indicates a casing suitable for inclosing the working parts of the transmitter and also serving as a support for these parts. A supporting arm 2 attached to a 80 U shaped member 4, which spans and is suitably attached to the outside of the casing 1, is pivoted at a bracket (not shown) and acts to carry the completely assembled transmitter. The casing 1 is tubularly formed and closed at one end, and as shown in the drawing, resembles a cup-like chamber placed in an inverted position. A disk 6 is attached to extension members 7 of the magnetic frame and a disk 8 of suitable diameter to 90 enter and close the lower end of the casing 1, is attached to the magnetic frame by means of the brackets 9. The diameter of the disk 6 is also less than the inside diameter of the casing 1; therefore the magnetic system of 95 the transmitter is completely inserted in the casing 1, in which position the disk 6 rests against the inside surface of the end section of the casing, and the disk 8 enters and seals the mouth of the casing chamber. 100 An opening 10, centrally located in the upper end portion of the casing 1, serves as a port through which the necessary exterior conductors enter the transmitter. A slotted opening 11, located at a uniform radial distance from the port 10, extends through a 90° section of the end portion of the casing 1. A screw-threaded bore extending through the disk 6, and into the frame extension 7, is located in alignment with the slot 11, and 110

therethrough receives a threaded screw 12. The flange or head of this screw is of sufficient diameter to overlap the edges of the slot 11; therefore, when fully seated, the screw 12 serves to clamp the complete transmitter assembly in the casing 1. The slot 11 and the clamping screw 12 provide that the transmitter assembly may be rotatively shifted to and clamped in either the position shown in Fig. 1, or the position shown in Fig. 2. It will be understood that this one-quarter rotative shifting of the transmitter assembly takes place within the casing 1 which remains in the position shown in Fig. 1 with respect to the supporting arm 2 and U member 4. In Fig. 2 the casing 1 is shown shifted one-quarter to the left merely for convenience in showing the manner in which the U member 4 is connected thereto.

In describing that portion of the transmitter assembly which pertains more particularly to the moving or vibrating parts thereof, a bridge member 14 in the form of a spider is rigidly clamped between nuts 15 carried by four screw-threaded studs 16 which project from and are supported by the disk 8. A piece of suitable resilient or damping material 17 resting in the bridge member 14, presses a rocking plate 18, having suitable bearing slots, against the knife-edged ends of two studs 19 carried by the disk 8. The bearing studs 19 engage the rocking plate 18 near its ends, and in the side view of this assembly, as shown in Fig. 1, are located behind and in alignment with the screw threaded studs 16 and therefore do not appear in this view. A bore extending through the rocking member 18 continues upwardly into the extension 20 of this member, and a bore of greater caliber in alignment therewith through the bridge 14, and the damping material 17 permits the shank of a stylus 21 to be inserted therein. The caliber of the bore through 14 and 17 gives entire clearance for the shank of the stylus 21, while the bore through 18 and 20 is of a caliber into which the stylus 21 is adapted to form a suitable fit. A set screw 22 carried by an enlarged base portion of the extension 20 and located at substantially the axis of rotation of the plate 18 serves to secure the stylus 21 rigidly to this plate. By locating the screw 22 at substantially the axis of rotation of the plate 18 and extending the stylus across this axis the movement of inertia of this portion of the lever system is materially reduced. A bore 23, extending centrally through the disk 8, is of a caliber sufficiently large to permit clearance for the member 20, which extends therethrough into the casing 1. A section of spring wire 24 serves to form a mechanical connection between the member 20 and an extension member 25 of an armature 26, the wire 24 being rigidly connected to each of the members so joined. The armature

26 is beveled to form a ridge which extends centrally across its face; therefore, when the armature rests centrally on the middle pole 28, it is adapted to execute a rocking movement thereon and cause corresponding variations in the air gap present between itself and the pole members 27 and 29. A bridge member 30 secured by means of screws 41 at each end thereof to extensions formed on the brackets 9, extends transversely over the armature 26 and presses a piece of suitable damping material 31 against the armature to hold it in position on the pole member 28. Two curved springs 32, rigidly attached to the bridge member 30, are adapted to rest on the spool heads of magnet poles 27 and 28, and exert pressure to retain the spools in position.

In the magnetic system, the windings 33 and 34 connect to a suitable source of unidirectional current (not shown) and serve to magnetize the pole members 27 and 29. The resulting magnetic flux completes circuit through the armature 26 and the common pole member 28 located midway between and acting magnetically differential with respect to the two pole members 27 and 29. The windings 35 and 36 respectively associated with the poles 27 and 29 represent the current reproducing coils, and when connected with a telephone receiver circuit (not shown), generate currents therein which correspond in strength and direction with the amplitude, rapidity and direction of movement of the armature 26, all in a well-known manner. Suitable terminals 37, 38, 39 and 40 are provided for terminating the windings 33, 34, 35 and 36, and for convenience in connecting the exterior conductors thereto.

In describing the operations which take place in transmitting vibrations from the stylus 21 to the armature 26, let it be assumed that a phonograph record grooved as shown in Fig. 5 is traveling from left to right and in proper contact with the stylus 21, the transmitter being held in the position shown in Fig. 2. The vertically formed indentations of the record-groove cause the stylus to be vibrated in a direction parallel to the direction in which the record is moving. Accordingly, the plate 18 rocks to and fro on the knife-edged bearings of the studs 19, and by means of the extension 20, alternate push and pull stresses are applied longitudinally to the spring wire member 24, which in turn sets up reciprocating or rocking movements of the armature 26. These movements of the tracing stylus 21 represent the tones which it is desired to reproduce, and as the spring member 24 is of such proportions as not to be appreciably flexed or buckled when push stresses are applied thereto longitudinally, it will be apparent that the effective vibrations are transmitted from the stylus 21 to the armature 26 over con-

nections in which elastic losses are practically avoided. In case the stylus is caused to vibrate in a direction at right angles to the travel of the record, however, such vibrations, provided they are not absorbed by the damping material 17, produce transverse stresses on the spring member 24, which is sufficiently flexible to yield thereto. Accordingly these transverse vibrations are absorbed and not transmitted to the armature 26. This feature results in eliminating such vibrations as do not form a part of the true phonograph record, thereby materially improving the distinctness and tone quality of the sounds reproduced in the telephone receiver. From the foregoing description in connection with the vertically grooved record, it will be apparent that when the transmitter is positioned as shown in Fig. 1 and a transversely grooved record similar to that shown in Fig. 4 is traced, the effective lateral vibrations of the stylus 21 will be transmitted to the armature 26 and any vertical vibrations will be absorbed by the spring 24.

In the matter of connecting the stylus 21 to the rocking plate 18, it will be noted that the set screw 22 and the enlarged portion of the extension 20 into which it is threaded, are practically in alinement with the bearing point present between the rocking plate 18 and the knife-edged bearing studs 19. This feature reduces to a minimum the inertia effect of the set screw 22, thereby materially increasing the effectiveness of the transmitter.

A further advantage of the present invention relates to the double motion reducing leverage system, the first of which is present with the rocking plate 18 whereby the point of the stylus 21, in tracing a record, moves a greater distance than the resulting movement at a point on the extension 20 at which the spring 24 is attached; the second motion reducing system being present with the armature extension member 25 which reduces the amplitude of the movement transmitted thereto by the spring member 24. Accordingly, the movement of the armature 26 is considerably less than the initial movement at the point of the stylus 21. This feature has an appreciable effect in overcoming the inertia and any momentum tendency of the necessarily heavy armature, and results in a considerable gain in the articulation and quality of tone reproduced. A further advantage of this double-levering system, which acts accumulatively, is to make it possible to condense the assembly of the transmitter and inclose it in a casing of relatively midget proportions, as shown and described. In order to protect the transmitter

from exterior vibrations and to cushion it at the position in which it is held, suitable damping washers 5 are interposed in the assembly between the supporting arm 2 and the U-shaped member 4 attached to the transmitter casing.

What is claimed is:

1. In a phonograph transmitter, a stylus, 70 a magnetic circuit, an inductive current circuit for said magnetic circuit, an armature for said magnetic circuit, and a plurality of motion-reducing leverage systems for connecting said stylus with said armature 75 whereby said armature is moved less than said stylus upon movement of the latter.

2. In a compact phonograph transmitter, a stylus, a magnet, an inductive current circuit for said magnet, an armature for said 80 magnet, a plurality of compact motion-reducing leverage systems for connecting said stylus with said armature whereby said armature is moved less than said stylus on movement of the latter, and a compact casing adapted to inclose and support the 85 completely assembled parts of said transmitter.

3. In a phonograph transmitter, means for generating electric currents, a stylus, 90 means for transmitting vibrations from said stylus to said current-generating means, a casing adapted to inclose and support said transmitter, means for assembling said transmitter independently of said casing, and means for changing the position of said 95 transmitter within said casing to adapt said transmitter to trace either a vertically grooved record or a transversely grooved record.

4. In a phonograph transmitter, a stylus, 100 a plurality of magnet poles, current inductive circuits for said magnet poles, an armature for said magnet poles adapted to be operated by said stylus, and a central transverse ridge formed on the face of said armature adapted to seat on one of said magnet poles and permit said armature to execute a rocking motion thereon in the flux zone of said magnet poles.

5. In a phonograph transmitter, a magneto 110 current-generating system, a stylus, a plurality of motion-reducing systems adapted to transmit vibrations from said stylus to said magnetic system whereby vibrations transmitted to said magnetic system by movement of said stylus are of smaller amplitude than corresponding vibrations of said stylus, and resilient damping material adapted to retain the working parts of said transmitter in their respective operating positions.

In witness whereof I hereunto subscribe my name this 10th day of March, A. D. 1916.

HENRY C. EGERTON.
